United States Patent

Des. 235,281
Patented June 3, 1975

235,281

TENT

George B. Madison, Haysville, and Eugene D. Lundblade,
Larry S. Thornton, Benjamin C. Baugh, and Lauren
D. Worley, Wichita, Kans., assignors to The Coleman
Company, Inc., Wichita, Kans.

Filed May 24, 1973, Ser. No. 363,395

Term of patent 14 years

Int. Cl. D21—04

U.S. Cl. D88—3 B

FIG. 1

FIG. 2

FIG. 3

FIG. 1 is a perspective view of a tent showing our new design;

FIG. 2 is a side elevational view of the tent of FIG. 1, the view from the opposite side being identical; and
FIG. 3 is an end elevational view showing the opposite end from that shown in FIG. 1.

We claim:

The ornamental design for a tent, as shown and described.
